CLAIM

The ornamental design for a pedestal vacuum cleaner, as shown and described.

DESCRIPTION

FIG. 1 is a front perspective view of a pedestal vacuum cleaner showing my new design;

FIG. 2 is a rear elevational view thereof;

FIG. 3 is a side elevational view thereof, the opposite side being a mirror image; and,

FIG. 4 is a top plan view thereof.

*Fig. 1.**Fig. 2.*

*Fig. 3.**Fig. 4.*
